UNITED STATES PATENT OFFICE.

THOMAS C. BALL, OF KEENE, NEW HAMPSHIRE.

INFANT'S CRADLE.

Specification of Letters Patent No. 22,056, dated November 16, 1858.

To all whom it may concern:

Be it known that I, THOMAS C. BALL, of Keéne, in the county of Cheshire and State of New Hampshire, have invented a new and useful Device for Rocking Cradles; and I do hereby declare that the following is a full and exact description of the same, reference being made to the annexed drawing, which is a perspective view.

10 The nature of this invention consists in having pieces, which are worked by cranks driven by springs, or other equivalent mechanism, arranged to lift alternately on opposite sides of a cradle, with sufficient force 15 to cause it to rock, or when it is set to rocking, to maintain the momentum and keep it in motion. It is constructed in the following manner:

A represents a portion of a cradle, to 20 which this is attached.

B is a frame work for the working parts. The spring and gearing for operating the cranks is incased therein, and is not shown in the drawing as such mechanism is well 25 known.

C, C, are the cranks which work the pieces D, D,—their crank pins are set at opposite points, so that D, D, strike alternately on the floor or surface on which the cradle 30 rocks, and lift on its opposite sides, to assist in reversing its motion and to give an impetus, sufficient to overcome its tendency to rest. D, D, are guided by the slot E, and crossbar F.

G is a key for winding up the spring, 35 which coils around the shaft H,—there is a toothed-wheel on the shaft H, which is connected to it by a ratchet and pawl, and receives motion thereby as the spring unwinds, it meshes with a small pinion on shaft I, which has another large wheel that works in pinions on the shafts of the cranks C, C, and transmits the motion to them. The motion of the cranks as the cradle rocks, acts as an escapement to regulate the un- 45 winding of the spring.

To put it in operation, the spring is wound up, by turning the key G, and the cradle being set in motion, the cranks C, C, and pieces D, D, operate in the manner de- 50 scribed to keep the cradle rocking, until the spring is run down, without requiring the attention of a person.

What I claim as my invention, and desire to secure by Letters Patent, is,

The arrangement of the cranks C, C, pieces D, D, slot E, and cross bar F, in combination with the spring and gearing operating in the manner explained, for the purposes specified.

THOS. C. BALL.
